UNITED STATES PATENT OFFICE.

JOHN HOSFORD, OF BOSTON, MASSACHUSETTS.

BUSTLE.

SPECIFICATION forming part of Letters Patent No. 366,217, dated July 12, 1887.

Application filed December 30, 1886. Serial No. 223,003. (No model.)

To all whom it may concern:

Be it known that I, JOHN HOSFORD, a citizen of the United States, and a resident of Boston, in the county of Suffolk and State of Massachusetts, have invented new and useful Improvements in Bustles, of which the following, taken in connection with the accompanying drawings, is a specification.

This invention relates to improvements in bustles, and particularly to improvements in the stays or springs by which the bows are united, and it is carried out as follows, reference being had to the accompanying drawings, in which—

15 Figure 1 represents a perspective view of a bustle provided with my improved stays or springs. Fig. 2 represents a vertical section over one of the stays or springs X, shown in Fig. 1, and Fig. 3 represents in section a modification of the improved stays or springs.

Similar letters refer to similar parts wherever they occur on the different parts of the drawings.

In Fig. 1 is represented a bustle, consisting 25 of a waistband, A, having side pieces, A' A', to which the ends of the spring-bows B, C, D, and E are riveted or otherwise secured, as usual. To said side pieces, A' A', is also secured, as usual, the spring-bow F, that is 30 adapted to rest on the back of the wearer when the bustle is in use.

a a are spring-stays uniting the waistband A and bow F. b b are similar stays uniting the spring-bows B and F, and c c are similar 35 stays uniting the spring-bows C and F, as is usual in bustles of this kind.

X X are bent or duplex springs or stays uniting the spring-bow D to the bows E and F, as shown in the drawings. Such bent or 40 duplex springs X are very liable to get broken at the sharp angle, where they are united to the bow D, when the legs of such springs X are

brought together, as may be caused by a lateral pressure on the bustle while the wearer is leaning against any unyielding object, or when reclining or lying down, causing derangement and destruction of the bustle. To prevent this, and to enable the duplex stays or springs X X to be expanded or contracted without causing breakage at or near the bend or angle, I bend it at such place in the form of a loop or eye, X', as shown in Figs. 2 and 3.

In Fig. 2 the eye X' is arranged centrally above the bow D, and in Fig. 3 such eye is shown as arranged on one side of said bow D. Either arrangement will answer the desired object.

d d are rivets, solid or tubular, by means of which the bow D is secured to one of the legs of the springs X near the eye X', as shown in Figs. 2 and 3.

Having thus fully described the nature, construction, and operation of my invention, I wish to secure by Letters Patent, and claim—

A bustle comprising the horizontal spring bows B, C, D, and E, the back-rest bow F, stays b c, connecting the upper bows, B C, with the back-rest bow, and the two springs X, riveted at their ends, respectively, to the back-rest bow and the lower horizontal bow, E, and having intermediate their ends the spring-loops X', elevated above the top horizontal edge of the bow D, the latter passing between the two members of each spring X and riveted thereto below the spring-loops, substantially 65 70 75 as shown and described.

In testimony whereof I have signed my name to this specification, in the presence of two subscribing witnesses, on this 24th day of December, A. D. 1886.

JOHN HOSFORD.

Witnesses:

ALBAN ANDRÉN,
HENRY CHADEOURN.
